EXPANSION DOWEL

Felix L. Nettleton, Kingston, N. Y.

Application February 18, 1949, Serial No. 77,225

5 Claims. (Cl. 94—8)

1
This invention relates to dowels for concrete expansion joints and is primarily intended for reinforcing and maintaining the alignment of the longitudinal joints in multi-lane highway pavements, although it is adaptable to all forms of concrete construction wherein natural expansion and contraction occurs.

In concrete road construction a longitudinal joint is provided to separate the pavement into parallel lanes where the width of the road makes this desirable in order to take care of transverse expansion and contraction due to changes in temperature or other causes. Such joints as heretofore used gradually widen due to shifting of the pavement on each side to a degree that is dangerous to high speed traffic and detrimental to the road bed. My invention aims to overcome this difficulty.

Further aims and objects of the invention are to maintain the horizontal alignment of the abutting edges of the pavement by preventing vertical movement of either edge independently of the other and to provide a simple and cheap form of dowel that can be installed easily as the pavement is laid.

With these purposes in view I have devised a form of dowel having only three separate parts, as illustrated in the accompanying drawings, wherein Figs. 1 and 2 are a plan view and a side view, respectively, of the assembled dowel; Figs. 3 and 4 are plan views of the male and female members, respectively, the socket portion of the female member being shown in section. Fig. 5 is a side view of the locking pin; Fig. 6 is a cross section of the assembled dowel taken on the line A—A in Fig. 1, looking in the direction of the arrows, and showing the locking pin in edge elevation; and Fig. 7 is a vertical cross section of a partly finished pavement, showing the dowel parts in position with the steel form after pouring the first section of concrete, the locking pin and joint packing as they appear in the finished pavement being shown in dot and dash lines.

In the dowel illustrated there are two bifurcated anchor members 10, 11 adapted to be embedded in the concrete, one on each side of the joint, and connected by a pin 12 which passes through slits 13 in the top and bottom walls of a tubular socket 14 welded to one of the anchor members and through a loop 15 formed between the two branches of the other anchor member. Each anchor member is preferably formed from rod or bar stock, doubled and bent to the shapes shown in Figs. 3 and 4, to provide diverging branches with terminal hooks or flanges 16.

2
The male anchor member 10 (see Fig. 3) has a spacing collar 17 welded to its loop end 15 where the branches diverge and spaced from the loop end far enough to permit the desired overlap between this end and the socket 14 of the female anchor member 11 in working position of the two members.

The female anchor member 11 (see Fig. 4) has a short loop portion 18 which is welded within 10 one end of the socket 14 so as to aline with the loop 15 of the male anchor member when the parts are in working position. The slits 13 in the top and bottom walls of the socket may be punched prior to forming the socket if the latter 15 is made out of flat steel plate, or cut or punched either before or after the flattening operation if the socket is made out of steel tubing.

The T-shaped locking pin 12 is advantageously stamped from sheet steel but may be forged or cast as preferred. This locking pin is preferably shaped to engage in the slits 13 in the top and bottom walls of the socket 14 as shown in Figs. 1 and 2, its width being sufficiently less than the length of the loop 15 to permit some play lengthwise of the loop 15 in the socket 14 when the parts are permanently assembled and embedded in the finished slab as hereinafter described. One of the branches 19 of the T is longer than the other for providing a slight adjustability of the female anchor member towards and away from the expansion joint in setting it in the concrete. The lower end of the narrow stem is cut at an angle to adapt it for retaining the male member in place during the pouring of the first section 25 of concrete.

The three parts of the dowel are readily fabricated and assembled for use, and may be placed in position and embedded in the concrete by unskilled labor. In constructing a road pavement 40 for example, illustrated in Fig. 7, the male anchor member 10 is supported by the form 21 with its loop end 15 projecting through a suitable opening in the form and its collar 17 against the inside face of the form, being held in position by the pin 12 which is placed sidewise in the projecting loop 15 with its long head against the web of the form and its narrow end wedged against the end of the loop 15. After the first section 20 45 is poured and the anchor member 10 is firmly embedded therein, the pin 12 is withdrawn and the form 21 is removed, whereupon one or more sheets of tarred felt or layers of mastic, cork or rubber or other joint packing 22 are placed against the edge of the section 20 of pavement as 50 is usual in such expansion joints, and the loop 55

ends 15 are punched through the packing and the sockets 14 of the female anchor members are slipped into place and locked by the pins 12, following which the adjoining section 23 of the slab is poured. For better illustrating this procedure, the anchor members and key are shown in Fig. 7 at right angles to the positions they would normally have in a roadway slab for reinforcing purposes, which would be as shown in Figs. 1, 3 and 4.

The longer branch 19 of the T-head of each pin engages against the outer face of the packing 22 (indicated by the dot and dash lines in Fig. 7) to secure it in place if only a slight expansion of the joint is desirable, and if more expansion is allowable the shorter branch of the T-head is placed in engagement with the packing, thus positioning the pin 12 with respect to the loop 15 where the expansion of the joint will be limited thereby to the extent desired.

In pouring continuous slabs intersected by transverse expansion joints the joint filling may be used to support the dowels during the entire operation instead of supporting them in forms temporarily, thereby permitting the pouring to proceed without interruption.

The invention is applicable to both longitudinal and transverse joints in any position to maintain the alinement of the slabs with flush surfaces as well as to control the amount of contraction and the widening of the joint, thus being adapted to roads, side walks, curbs and gutters, walls, pipe, and other structures embodying large blocks of concrete or construction joints where open cracks are deleterious.

The invention is not restricted to the particular shapes and sizes of the dowel elements, as obviously these may be varied to suit the kind of structure in which the joint is formed.

What I claim and desire to secure by Letters Patent is as follows:

1. A three part dowel for controlling the expansion of construction joints in concrete structures comprising a pair of anchor members formed of rods bent at the middle to provide elongated loops, the ends of said rods diverging to constitute anchor elements, a socket integrally secured on the end of the loop portion of one anchor member and adapted to receive the loop portion of the other anchor member, said socket having transversely elongated openings in its opposite side walls to receive a locking pin, and a thin wide locking pin passing through said openings and between the sides of the loop portion of said second anchor member preventing withdrawal thereof from said socket and permitting limited lengthwise movement thereof in said socket.

2. The combination as set forth in claim 1, wherein said other anchor member is provided with an integral spacing collar adjacent the inner end of its loop portion.

3. The combination as set forth in claim 2, wherein the locking pin has a laterally extending head adapted to engage a positioning element between it and said spacing collar.

4. A limited movement joint assembly for connecting adjacent concrete slabs comprising interengaged male and female anchor members embedded in said slabs one on each side of their juncture, said male anchor member projecting across said juncture and said female anchor member having a tubular extension slidably fitting the projecting end of the male anchor member, a locking pin having a stem passing through alining openings in said tubular extension and in said projecting end, the opening in said male anchor member being longer than the width of said locking pin providing limited capacity for movement of said male anchor member with respect to said locking pin while preventing withdrawal of said male anchor member from said female anchor member, said locking pin having a transverse head providing a lateral limit stop serving to position it and said female anchor member in spaced relation to said juncture during the formation of the slab in which they are embedded.

5. The method of constructing a connecting joint between concrete slabs, said joint comprising interengaged male and female anchor members embedded one in each of said slabs and connected by a transverse pin also embedded in one of said slabs, said pin having a T-head and passing through alining openings in said anchor members, the opening in said male anchor member being elongated, which method consists in positioning the male anchor member in a perforated marginal form with its anchor end on the side thereof toward the slab to be poured and its pin opening on the opposite side of the form, temporarily securing said male anchor member in position in said form during the pouring of said slab by said pin arranged transversely in said opening with its head flatwise in contact with said form, thereafter removing said pin and form, and positioning the female anchor member with its openings in alinement with the opening in the male anchor member, securing the two anchor members together by inserting said pin through said alined openings with its stem parallel to the edge of and in spaced relation to said first poured slab, and pouring said second slab to embed said pin and female anchor member.

FELIX L. NETTLETON.
